UNITED STATES PATENT OFFICE.

EDWIN S. LEAYCRAFT, OF NEW YORK, N. Y.

PNEUMATIC DISPATCH-TUBE RECEIVER.

SPECIFICATION forming part of Letters Patent No. 242,458, dated June 7, 1881.

Application filed November 17, 1880. (No model.)

To all whom it may concern:

Be it known that I, EDWIN S. LEAYCRAFT, a citizen of the United States, and a resident of the city, county, and State of New York, 5 have invented a new and useful Improved Receptacle or Receiver, which shall receive the parcel-carrier of a pneumatic dispatch-tube without injury to the carrier or receiver; and I do hereby declare that the following, taken 10 in connection with the accompanying drawings, is a full, clear, and accurate description of the same.

In the drawings, Figure 1 represents a side view of my improvement. Fig. 2 shows a plan 15 view.

I make my receiver as follows:

A shows the outlet of a pneumatic tube, and B my improved receiver.

The receiver B is made in the form of a scroll 20 or volute, the inlet end of which scroll is arranged concentric and parallel with the axis of the pneumatic tube. The said scroll or volute—formed preferably of four rods—is made 25 with the curve of the scroll diminishing from the inlet end of the scroll, at the point where

the parcel-carrier is received from the pneumatic tube, toward the outlet end of the scroll. The scroll B, formed in this manner, has a twist which increases from its inlet end toward its outlet, so that the parcel carrier, as it is ejected 30 from the pneumatic tube and received in the scroll, has its force distributed over the inner surface of the scroll, thereby producing friction sufficient to entirely avoid the shock of its ejection, whether the parcel-carrier is lightly 35 or heavily loaded.

Having thus described my improvement, what I claim, and desire to secure by Letters Patent, is—

In combination with a pneumatic dispatch-tube, the receiver B, formed in a scroll, with the curve of the same diminishing from its inlet toward its outlet, substantially as described, and for the purposes set forth.

In testimony whereof I have hereunto set 45 my hand this 16th day of November, 1880.

EDWIN S. LEAYCRAFT.

In presence of—
CHARLES G. COE,
LOUIS W. FROST.
